UNITED STATES PATENT OFFICE

CHANDOS CHARLES WILLIAMS, OF DETROIT, MICHIGAN

POCKET CASH REGISTER

Application filed June 1, 1926. Serial No. 113,026.

This invention relates to cash receiving and accounting devices and relates particularly to pocket devices serving the purpose both of a purse and a register of expenditures.

5 It is an object of the invention to provide a compact device comprising a receptacle for coins and other currency, and a highly simplified means for listing expenditures.

Another object is to adapt the accounting 10 means to carry a movable sheet of paper and to permit a free removal from the device of said means as a unit, so as to facilitate the renewal of the paper.

A further object is to provide for mounting 15 the traveling sheet of paper upon a frame consisting of a single sheet metal stamping such as may be produced in quantities at little expense.

These objects the invention attains by the 20 construction herein described, and illustrated in the accompanying drawings, wherein:

Figure 1 is a perspective view of the invention, showing the cover thereof raised, as 25 when an entry is to be made.

Figure 2 is a cross-sectional view of the device.

Figure 3 is a plan view of the accounting unit.

30 Figure 4 is an end view of said unit.

Figure 5 is an end view of a slightly modified accounting unit.

In these views, the reference character 1 designates a shallow open-topped receptacle 35 formed of sheet material, having strength, durability and flexibility, such as leather. This receptacle has a marginal upstanding wall 2 at its ends, and a front marginal wall 2^a, and its rear margin is connected, preferably integrally, with a main cover member 3 having a marginal wall 4 corresponding to that of the receptacle 1 and adapted to fit within said receptacle. A connecting portion 5 of the body of said receptacle and cover member 40 exercises a hinge function, adapting the cover member to swing freely to or from its covering positions, shown in dash lines in Figure 2.

Within the receptacle 1, there is secured a 50 false bottom 6, preferably of flexible sheet

material, which co-acts with the true bottom of said receptacle to form a pocket 7 for receiving coins or other currency. The member 6 is cemented or stitched to the end walls 2 and front wall 2^a but is free at its edge adjacent the hinge 5 so as to provide an inlet 8 to the coin pocket.

The receptacle 1 receives an accounting device consisting primarily of a frame 9 and an elongated paper sheet 10 carried by said frame. It is preferred to form the frame 9 of sheet-metal and the illustrated construction is such as to permit said frame to be formed from a single sheet metal stamping. Thus said frame comprises a flat table portion 11 adapted to support that span of the sheet 10 upon which entries are to be made. Forwardly of said table portion, the frame is bent to extend downwardly as indicated at 12, and the base of the portion 12 forms a trough-shaped keeper 12^a for a paper roll 10^a which is the initial form of the sheet 10. A curved tongue 13 integrally rises from the forward edge of the keeper 12^a engaging the center portion of the roll 10^a holding said roll 75 in the keeper and guiding the sheet of paper as it advances to the table portion 11 of the frame. It is to be noted that said tongue terminates adjacent to said table portion and slightly below the upper face thereof so as to hold the paper down upon said face.

Rearwardly of its table portion, the frame 9 is downwardly bent, as indicated at 14, to form a support for said portion, and a pair of tongues 15, integrally projecting from the ends of said portion are bent downwardly adjacent to the support 14 to journal pins 16 mounting a pair of companion feed rolls 17. Above said rolls and extending parallel thereto is a slot 18 in the table member of the frame, through which slot the paper sheet passes downwardly to engage the rolls 17. Said rolls may be faced with rubber or some similar material to adapt them to more firmly engage the sheet 10. Said sheet, after leaving said rolls, is adapted to accumulate beneath the table portion 11, as indicated at 10^b. It will be seen that the depending forward and rear portions 12 and 14, resting upon the false bottom 6, elevate the table por-

tion 11 and form, beneath said portion a chamber 19 which receives the used portion 10^b of the paper. When necessary, the accumulated used paper may be torn from the 5 main sheet and the entries thereon totaled. As is best seen in Figure 4, the sheet may be stressed against the lower edge of the part 14 of the frame so that the tear will occur along a straight line.

10 To the rear edge of the false bottom, there is cemented, or otherwise permanently attached, an inner or intermediate cover member 20 flanged at its ends and at its margin remote from the false bottom as indicated at 15 21 and the flange 21 being adapted to fit within in the receptacle 1, when said cover member is in its covering position. When in said position, a rectangular opening 22 in said cover member exposes that portion of the sheet 10 resting upon the table 1, so that an entry or 20 entries may be made upon said sheet. A sufficient free portion 23 of the fabric forming said cover member extends between the body of said member and the false bottom to serve 25 as a hinge. It is preferred to make some provision in the way of a catch or fastening to hold the cover member 20 normally in its closed position. The illustrated fastening means consists of a short strap 24 secured to 30 the flange 21, in such a manner as to be passed snugly through a slot 25 in the wall 2^a of the receptacle as said flange engages said wall.

To provide for actuating the rolls 17, the pin mounting one of said rolls may carry a 35 serrated wheel 26 or other actuating member at one end of the frame 9, and said wheel may project, as seen in Figures 1 and 2, through a slot 27 in the cover member 20 so as to be exposed when the outer cover 3 is raised.

40 A pair of tongues 28 formed integrally with the ends of the frame 9 are bent toward each other and spaced slightly above the table 11 to co-act with the tongue 13 in holding the sheet in close contact with the table.

45 To complete the described device, it is adapted to carry a pencil 29 for making entries upon the sheet 10. Thus apertures 30 and 31 are formed in one of the ends 2 of the receptacle and in an end portion of the flange 4; said apertures registering when the cover member 20 is in covering position, and said pencil, when inserted in said apertures, is engageable, within the chamber 19, with a keeper 32 formed by a tongue struck inwardly from an end portion of the table 11. The tongue 32 further acts as a guide for the used portion of the sheet as it accumulates beneath the table, facilitating the rolling of said sheet.

50 The modified form of accounting device 60 illustrated in Figure 5 differs from the described construction only in that the end lugs 15' of the frame mount only a single roll 17', the sheet 10' being frictionally engaged and fed between said roll and the depending portion 14' of the frame.

It is a feature of the construction, that the accounting device (in either of its disclosed forms) is freely removable as a unit from the receptacle 1, thus simplifying the manufacture and original assembly and permitting a user of the article to very easily effect a renewal of the sheet 10 or to tear off the used portion of the sheet.

70 It is to be noted that the construction makes for simplicity, furthermore, in that there is avoided the use of shafts or rollers to carry either the unused or used portions of the sheet.

75 Preferably the receptacle 1, and its cover members 3 and 20 have an approximate wedge form, reducing in thickness as they approach the edge of the article at which the cover members are hinged. This shape permits the article to be carried more conveniently in a hip pocket.

80 By adapting a single article to serve both as a purse and as an accounting device, the user of the article is definitely reminded to make an entry of an expenditure in getting 85 out the amount to be spent, and time is saved in eliminating the handling of a notebook or the like additionally to the handling of a purse.

85 In order that the false bottom 6 may present a flat supporting surface to the registering device, it is preferred to form said bottom, at least in part, of sheet metal, or some other relatively rigid material. Thus in 90 Figure 2 a sheet metal plate 33 is secured to the member 6 within the coin pocket 7. The means shown for attaching said plate to said member consists of tongues 34 on said plate passed through said member and bent down.

95 It will be noted that the flanged cover 3 forms a holder into which coins may be slid 100 from the pocket 7 to permit a ready selection of any desired coin or a summing up of all of the coins.

105 What I claim is:

110 1. A recording device comprising a sheet of material having a table portion for supporting a record receiving portion of a record sheet, and having downturned supporting portions at opposite sides of said table portion, one of said supporting portions forming 115 a receiver for a rolled supply portion of the record sheet, and the other downturned portion being formed with a slot, a pair of end bearing members upon said slotted downturned portion, and a feed roller for said sheet journaled in said bearing members, the record sheet being adapted to pass from said feed roller through said slot and into a chamber for the used portion of the sheet formed 120 below said table portion, and between said supporting portions.

125 2. A mounting of sheet material for a travelling record sheet, comprising a trough shaped receiver for a rolled supply portion of 130 said record sheet, a table member integrally

extending from one edge of said receiver and a wall integrally projecting downwardly from said table member at its opposite edge and spaced from said receiver to provide a receptacle for a used portion of the record sheet between said wall and receiver, and having an opening for the passage of the record sheet into said receptacle.

3. A mounting of sheet material for a travelling record sheet, comprising a trough shaped receiver for a rolled supply portion of said record sheet, a table member integrally extending from one edge of said receiver, and a wall integrally projecting downwardly from said table member and at its opposite edge spaced from said receiver to form a receptacle for a used portion of the record sheet and slotted for the passage of said sheet into said receptacle.

20 4. A mounting of sheet material for a traveling record sheet, comprising a trough-shaped receiver for a rolled supply portion of said sheet, a table member integrally extending from one edge of said receiver and integrally formed with a down-turned edge portion remote from said receiver, said down-turned portion coacting with the receiver to support said table member and to form beneath the table member a receptacle for a used portion of the record sheet, the table member being transversely slotted for the passage of the record sheet into said receptacle.

35 5. A mounting of sheet material for a traveling record sheet, comprising a table member having end portions down-turned to form supports for said table member and to further form, beneath said table member, a receptacle for a used portion of the record sheet, said table member being transversely slotted for the passage of the record sheet into said receptacle, and means integrally carried by one of said down-turned portions for mounting a supply portion of the record sheet.

45 In testimony whereof I sign this specification.

C. CHARLES WILLIAMS.
